UNITED STATES PATENT OFFICE.

JAMES G. HARDIE, JR., OF CANTON, NEW YORK.

MAILING-MACHINE.

SPECIFICATION forming part of Letters Patent No. 378,309, dated February 21, 1888.

Application filed June 8, 1887. Serial No. 240,647. (No model.)

To all whom it may concern:

Be it known that I, JAMES G. HARDIE, Jr., a citizen of the United States, residing at Canton, in the county of St. Lawrence and State 5 of New York, have invented a new and useful Improvement in Mailing-Machines, of which the following is a specification.

My invention relates to an improvement in mailing-machines for addressing newspapers 10 and other periodicals; and it consists in the peculiar construction and combination of devices, that will be more fully set forth hereinafter, and particularly pointed out in the claims.

In the drawings, Figure 1 is a perspective view of a mailing-machine embodying my invention. Fig. 2 is an elevation of the opposite side of the machine. Fig. 3 is a front elevation of the same. Fig. 4 is a vertical longitudinal sectional view. Fig. 5 is a vertical 20 transverse sectional view taken on the line *x*-*x* of Fig. 4.

A represents a rectangular metallic case, which comprises the main frame or body of the mailing-machine, and has its front and 25 rear ends open and its upper side removed for a suitable distance from its front end.

B represents an inverted-U-shaped metallic yoke the central portion of which is arranged transversely on top of the frame or case A, and the vertical arms of which bear against 30 opposite sides of the case and are secured thereto by means of screws. These vertical arms constitute guides C, and are provided on their front sides with vertical grooves.

D represents vertical metallic guides, which are screwed to the sides of the case A at a suitable distance in advance of the guides C and are provided on their rear edges with vertical grooves. From the central portion of 35 the yoke B projects a vertical handle, E, which is adapted to be grasped by one hand of the operator. To one side of the case A, near the lower edge thereof, is secured an outwardly-extending bracket-arm, F.

G represents a stationary transverse cutting blade or jaw which is secured on the front side of the case A at the lower edge thereof, and one end of the said stationary jaw projects beyond one side of the case.

H represents the longitudinal rock-shaft, which has its rear end journaled in the outer

end of the bracket-arm F, and the front portion of the said rock-shaft extends through and is journaled in a transverse opening in the projecting end of the jaw G. The front 55 end of the rock-shaft H is squared for a suitable distance in front of the jaw G, and on the said squared portion of the shaft is secured one end of a rocking jaw or cutter, I. The outer extremity of the shaft H is screw-threaded, and 60 on the said threaded portion of the shaft is fitted the clamping-nut K, which bears against the outer side of the jaw I.

L represents a flat spring which has one end fitted on the threaded end of the shaft, 65 and the free end of the said spring bears rearwardly against the free end of the jaw I and fits in a recess, M, made in the frontside thereof.

N represents a clamping-nut which works on the threaded end of the shaft and bears 70 against the inner end of the spring, thereby securing the latter between the nuts K and L. Near the rear end of the shaft H is secured a gear-pinion, O.

P represents an operating-frame which is 75 substantially U-shaped, and has a central transverse portion arranged under the case A, and its vertical arms R embracing opposite sides of the case A and provided on their front and rear edges with vertical tongues which 80 engage the opposing grooves in the guides C and D. The operating-frame is thereby rendered vertically movable on the case, as will be readily understood. Through the outer side of one of the vertical arms R is bolted a 85 depending vertical arm, F', which is provided on its inner side with rack-teeth that engage the teeth of the pinion O.

T represents a pair of flat springs which have their central portions secured on pins 90 that project upward from the central portion of the operating-frame, and the extended ends of the said springs bearing against the bottom of the case A, thus causing the springs to exert a constant downward pressure on the 95 operating-frame.

U represents the transverse shaft, which is journaled in the side walls of the case A immediately in rear of the stationary jaw G. The said shaft is provided at suitable distances 100 from opposite sides of its center with spur-wheels V, and one end of the said shaft, which

projects beyond the side of the frame, is provided with a gear-wheel, W, which is rigidly secured thereto.

On the opposing sides of the frame A, at the front edge thereof, are secured vertically-adjustable bearing-plates X, in which is journaled a transverse shaft, Y, which shaft extends through vertical openings Z, with which the side walls of the case are provided. One end 10 of the said shaft projects beyond the rock-shaft H and has a milled thumb-nut, Z'. The opposite end of the shaft has rigidly secured to it a spur-wheel, A', which meshes with the wheel W, and on the outer side of the said 15 spur-wheel A' is a rigid ratchet-wheel, V', the teeth of which are arranged at suitable distances apart. From one of the vertical arms R of the operating-frame P projects a forward-extending arm, C', to the outer end of which 20 is pivoted a spring-actuated pawl, D', adapted to engage the ratchet-wheel V'. On the central portion of the shaft Y is a roller, E', which is preferably made of hard rubber, but may be made of other suitable material, and the 25 said roller bears against the upper sides of the spur-wheels V.

F² represents a reservoir for paste, which is adapted to fit in the case A and to slide longitudinally therein. The front side of the 30 said reservoir is inclined downward and forward, and in the lower edge thereof is made a transverse opening, G'.

H' represents a pair of bearing-blocks, which are secured on the front side of the reservoir, 35 and in the said bearing-blocks are journaled the projecting spindles of a roller, I', which roller is preferably made of hard rubber and is arranged to cover the opening G'.

K' represents the metallic strap or plate, 40 which is screwed to the inclined front side of the plate S', and is provided at its front ends with a transverse slot, L', arranged immediately above the roller I'. On the rear side of the case or reservoir F² is a screw-cap, M', which 45 covers an opening in the reservoir through which paste may be introduced thereto. In the under side of the top of the case A is a longitudinal shallow groove, N'.

O' represents a flat spring which is secured 50 on the upper side of the case A, and has a depending stud at its rear extremity, which stud extends downward through an opening in the top of the case and is adapted to enter a recess in the upper side of the reservoir, and 55 thereby retain the latter in position when inserted in the case A.

The operation of my invention is as follows: A strip of paper, a, on which the addresses are printed in the usual manner, is inserted 60 through the groove N', and from thence passes downward through the slot L' and bears on the upper side of the roller I', and then passes forward between the roller E' and the spurred wheels V, which spurred wheels impinge 65 against the under side of the paper, and are thereby adapted to move it forward at each partial rotation of the shaft U. The pressure

of the springs T against the operating-frame P causes the same to be normally lowered from the case A, and the rack-arm F', by meshing 70 with the pinion O, to partly turn the shaft H, and thereby raise the jaw or blade I nearly to a vertical position. By means of the milled nut Z' the roller E' is first turned by hand to cause the front ends of the paper strip a to be 75 projected a suitable distance beyond the front edge of the stationary jaw G. It will be observed that as the said strip is moved forward it causes the roller I' to rotate, and, as the latter communicates with the paste in the reservoir, it applies paste to the under side of the paper strip. The operator grasps the handle E with one hand and brings the machine down 80 forcibly upon the newspaper to be mailed, thereby causing the frame P to move upward 85 against the pressure of the springs T, and causing the rack-arm F' to turn the pinion O through nearly a quarter of a circle, and thereby swing the jaw I to a horizontal position. As the edge of the said jaw passes the 90 edge of the rigid jaw G, the projecting portion of the paper strip, on which an address is printed, is severed, and the said severed portion of the paper is carried downward by the jaw I and pasted upon the newspaper. When 95 the machine is lifted from the newspaper, the springs T, in forcing the frame P downward, cause the pawl D' to engage one of the ratchet-teeth of the wheel V', and thereby partly turn the shaft Y a sufficient distance to cause the 100 paper to be moved forward, so that another address is projected beyond the jaw G, when the operation before described is repeated. The spring L, by pressing against the outer end of the jaw I, causes the said jaw to bear 105 snugly against the front side of the jaw G as it descends, and thereby effect a clean cut of the paper strip.

Having thus described my invention, I claim—

1. In a mailing-machine, the combination of the case A, having the rigid jaw G at its front side, the rock-shaft H, journaled on one side of the case and having the swinging jaw I and the pinion O, the vertically-movable frame P, having the rack-arm engaging the pinion O, and the springs to normally lower the said frame P, for the purpose set forth, substantially as described.

2. In a mailing-machine, the combination 120 of the case having the rigid jaw G at its front side, the rock-shaft on one side of the case, having the swinging jaw I, the spring L, bearing against the front side of the said swinging jaw, and the vertically-movable operating-frame geared to the rock-shaft, for the purpose set forth, substantially as described.

3. The combination, in a mailing-machine, of the case A, the shafts U and Y, journaled in the said case and geared together, said shaft U having the spurred wheels V and the shaft Y having the roller E' and the ratchet-wheel V', the vertically-movable frame P, having the arm C', the spring-actuated pawl D', depend-

ing from the said arm and adapted to engage the ratchet-wheel, and the springs T, to move the frame P downward normally, and thereby cause the pawl V' to partly turn the shafts V 5 and Y by engaging one tooth of the pawl, substantially as described.

4. In a mailing-machine, the combination of the case A, having the feed mechanism and the operating cutting-jaws, and the paste-reservoir F², adapted to fit in the case A and to be detached therefrom, said reservoir having the opening G' at its lower front side, the paste-roller I', journaled on the front side of the reservoir, removable therewith, and arranged over the opening G', and the strap or plate having the slot L', to guide the paper strip over the roller I', substantially as described.

5. In a mailing-machine, the combination of the case A, having the feed mechanism and the cutting mechanism, and the longitudinal groove N' in the under side of its top, the reservoir F², adapted to fit in the said case and provided at its front end with the pasting-roller and the guide for the paper, and the 25 detent to lock the reservoir in place in the case A, substantially as described.

6. A mailing-machine having a removable paste-reservoir provided at its rear end with an opening for the admission of paste, the 30 opening G' in its lower-front corner, the blocks H' on the front side of the reservoir, the roller I', journaled in said blocks and arranged over

the opening G', and the strap or plate K', secured to the front end of the reservoir, extended over the roller, and having the slot L', 35 substantially as described.

7. In combination with the case A, the vertically-movable operating-frame having a vertical handle on its upper side, the paste-reservoir arranged under the handle, the guiding-groove for the paper formed between the top of the reservoir and the lower end of the handle, the roller I', closing the outlet to the reservoir, journaled on the front side of the same, and removable therewith, and the plate K', with slot L', arranged above the roller I' and secured to the reservoir, substantially as described.

8. In a mailing-machine, the combination of the case A, having the rigid jaw G on its front side, the rock-shaft journaled on one side 50 of the case, the cutting-jaw I, attached to the said rock-shaft, and the spring-actuated vertically-movable frame geared to the rock-shaft and extending below the case, being thereby adapted to be operated by contact with the object on which the machine is downwardly pressed, substantially as described.

In testimony that I claim the foregoing as my own I have hereto affixed my signature in presence of two witnesses.
